UNITED STATES PATENT OFFICE.

DAVID I. STAGG, OF NEW YORK, N. Y.

IMPROVED BOOK-HOLDER.

Specification forming part of Letters Patent No. 55,924, dated June 26, 1866.

To all whom it may concern:

Be it known that I, DAVID I. STAGG, of the city, county, and State of New York, have invented a new and Improved Book-Holder; and I do hereby declare that the following is a full, clear, and exact description thereof, which will enable those skilled in the art to make and use the same, reference being had to the accompanying drawings, forming part of this specification, in which—

Figure 1 is a plan or top view of my invention; Fig. 2, a side sectional view of the same, taken in the line *x x*, Fig. 1.

Similar letters of reference indicate corresponding parts.

This invention relates to a new and improved device for holding books in an open state, so that the same may be read without the necessity of holding them open with the hands.

The object of the invention is to obtain a simple, neat, and cheap device for the purpose specified, and one which may be adjusted to suit books of different thicknesses, or those having a greater or less number of leaves, and to hold the book open equally well with a greater or less number of leaves at either side.

A represents a platform or base, the front edge of which is beveled or inclined, and has a cleat or strip, *B*, attached extending its whole length. This strip *B* has an oblong narrow slot, *a*, made longitudinally through it, or the upper surface of said strip may be notched or hollowed out and have a cleat secured to or nailed to its ends, and in this slot *a* two arms, *C C*, are secured by pivots or screws *b b*. These arms *C* are of such dimensions that they may be shoved in the slot *a* when not required for use, so as to be entirely out of the way, and the outer ends of the arms *C* are slotted longitudinally and vertically, as shown at *b'*, to receive fingers *D*, which are pivoted in the slots by pins *e*, passing horizontally through the arms, the fingers being capable of being turned

down within the slots in the arms or raised up out of them.

The cleat or strip *B* serves as a support for the lower edge of the book, the back of the book being supported by a frame composed of two inclined bars, *E E*, attached one to each side of the front part of the platform or base and cross-bars *F*, which connect the bars *E E*, the bars *E E* being braced from the rear end of the platform or base by inclined bars *G*.

In adjusting a book to the holder the former is opened and placed against the inclined frame with its lower edge resting on the cleat or strip *B*. The arms *C C* are drawn out and the fingers *D* turned up to hold the leaves back at each side of the book and to hold the book against the support. The arms *C* may be brought more or less outward to suit the thickness of the book or the number of leaves at each side of the same, and the arms, in consequence of being movable independent of each other, may be adjusted to suit the thickness of the leaves at either side of the book. The arms *C C* are prevented from moving casually by screwing up the screws *b b*.

The platform or base *A* may be attached to a stand or support, if desired, and the frame of the device made or arranged so as to fold down out of the way when not required for use.

Having thus described my invention, I claim as new and desire to secure by Letters Patent—

The arms *C C*, secured in the cleat or strip *B* by screws *b b*, and provided with pivoted fingers *D* at their outer ends, in connection with the inclined frame and base, all arranged substantially as and for the purpose specified.

DAVID I. STAGG.
